UNITED STATES PATENT OFFICE.

MAX SCHNEFEL, OF NEWARK, NEW JERSEY, ASSIGNOR TO SCHNEFEL BROTHERS, INC., OF NEWARK, NEW JERSEY, A CORPORATION OF NEW JERSEY.

FINGER-NAIL CLIP.

Application filed March 19, 1928. Serial No. 262,709.

This invention relates to finger nail clips for toilet purposes, and has for its object the production of such an implement comprising the fewest practicable parts, each 5 individually detachable, and which has no pivot pin, and can be readily taken apart and put together again without the use of tools.

The invention includes the three separable 10 parts illustrated in the accompanying drawings, of which Fig. 1 represents a side view of one of the jaws, and Fig. 2 a top view thereof looking at the flat side or face of the jaw. Fig. 3 is a side view of the complementary jaw, and Fig. 4 is a bottom or 15 flat face view of the jaw. Fig. 5 is a side view of the two jaws in engagement without the spring. Fig. 6 is a top view of the V-shaped spring, and Fig. 7 is a bottom view 20 thereof. Fig. 8 is a side view of all the parts assembled. Fig. 9 is a sectional view of the cutter spring taken upon the broken line 9—9 of Fig. 7.

The scale of drawing is double the actual 25 size of this invention to render the construction clearer, and throughout the drawings and description the same number is used to refer to the same part.

Considering the drawings, the jaw 1 has 30 the offset projections 2 and 3 provided near their extremities with the small transverse grooves 4 and 5. Between the projections is a space marked 6.

Figs. 3 and 4 illustrate the second jaw 7 35 having a single offset projection at the jaw end provided with the transverse groove 9.

By introducing the single projection 8 of jaw 7 into the space 6 of the end of jaw 1, the two jaws may be associated as illustrated 40 in Fig. 5. The jaws may be provided with small holes 10 and 11 at their free ends, intended to engage a clip or key-ring as shown in Fig. 5, and which will hold the jaws together.

In Figs. 6 and 7 and 9 the V-shaped cutter spring is referred to as a whole by the number 12. The spring has a curving cutting edge 13, and a recess 14 in its rear. On one side or face of the spring is formed a single depression 15, and on the other face the two spaced depressions 16 and 17. In Fig. 9 it will be noted that the cutting edges 13 slant towards each other, and that by reason of the formation of the depression 16 and the other depressions, a ridge or

shoulder 19 is formed between the depression and the cutting edge. In assembling the parts the projections 2 and 3 of jaw 1 engage the spaced depressions 16 and 17, and the ridges between those projections and 60 the cutting edge of the spring enter grooves 4 and 5. Similarly the projection 8 seats itself in depression 15, and the adjacent ridge engages groove 9.

In operation, if the jaws are opened as 65 shown in Fig. 8 the spring 12 may be positioned or removed by bringing its cutting edges together with the fingers, no tool being called for.

The clasp or key-ring 18 may be of any 70 selected pattern, and the clip as a whole, usually ornamental in design externally, may be carried attached to a watch chain or the like.

It will now be understood that only three 75 parts are required to complete this invention, that it has no pivot pin or rivet, and that the parts are freely detachable and as easily assembled, resulting in a very effective and convenient clip for cutting the 80 finger nails.

Having now described this invention and explained the manner of its operation, I claim:

1. A nail clip, comprising separable jaws 85 provided at the ends with oppositely offset projections, the said projections being constructed to engage each other leaving a space between the jaw ends, each of the said projections having a transverse groove 90 near its extremity, and a cutter spring located in the said space and having ridges arranged in engagement with the said grooves of the projections whereby the jaws are maintained in engagement against 95 displacement in the direction of the length of said jaws and the said spring is held in operative relation to the jaws and against displacement therefrom.

2. A nail clip comprising jaws separable 100 bodily, one of said jaws having at its end a portion formed into a pair of spaced offset projections, a second jaw having a single off-set projection passing between the said spaced projections of the first jaw, 105 the projections of both jaws having transverse grooves at their extremities, and a cutter spring having a rear recess receiving and engaging the outer sides of the said pair of projections of the first jaw 110

whereby the spring is held against displacement sidewise, the said cutter spring being located between the said projections of the jaws as shown and constructed and arranged to engage the said grooved ends of the said projections, the expansion of the said spring acting to keep the jaws to-

gether in operative relation and prevent relative displacement of said jaws in the direction of the length of the jaws. 10

In testimony whereof I affix my signature.

MAX SCHNEFEL.
